UNITED STATES PATENT OFFICE

97,437

DESIGN FOR A BUS SIGNAL SIGN

Albert G. Love, Taft, Calif.

Application July 16, 1935, Serial No. 57,668

Term of patent 7 years

To all whom it may concern:

Be it known that I, Albert G. Love, a citizen of the United States, residing at Taft, in the county of Kern and State of California, have invented a new, original, and ornamental Design for a Bus Signal Sign, of which the following is a specification, reference being had to the accompanying drawing, forming part thereof.

The figure is a tilted elevation of a bus signal sign, showing my new design.

I claim:

The ornamental design for a bus signal sign substantially as shown.

In testimony whereof I affix my signature.

ALBERT G. LOVE.
